UNITED STATES PATENT OFFICE.

WESLEY G. NICHOLS, OF CHICAGO HEIGHTS, ILLINOIS, ASSIGNOR TO AMERICAN Manganese STEEL COMPANY, OF CHICAGO, ILLINOIS, A CORPORATION OF MAINE.

CAST-STEEL RAILWAY-TRACK MEMBER.

Application filed July 28, 1922. Serial No. 578,043.

To all whom it may concern:

Be it known that I, WESLEY G. NICHOLS, a citizen of the United States, residing at Chicago Heights, in the county of Cook and State of Illinois, have invented certain new and useful Improvements in Cast-Steel Railway-Track Members, of which the following is a specification.

This invention relates to railway track members constructed of cast steel, such, for instance, as frogs, switches, switch points, mates and crossings, and particularly to track members produced by casting steel, for instance, manganese steel, having a composition which necessitates uniform heat treatment throughout the mass in order to bring the steel to its condition of highest resistance to the wear which it encounters in service.

Track members constructed of cast manganese steel have been found to resist wear phenomenally, but they have not developed proper resistance to shocks when constructed in accordance with practice heretofore followed. When the section of the metal has been restricted to insure proper heat treatment, cracks have developed particularly at the intersection of flangeways, and when the metal has been increased in thickness under points of weakness thus developed, excessive pounding down of points, flowing of metal into flangeways, and other distortions have been observed.

The object of the present invention is to provide a construction of cast steel track members which will afford ample strength to resist cracking in weaker parts, which will admit of thorough heat treatment to develop the highest character of the steel alloy employed, and which will, particularly in the preferred construction, afford superior support to the vertical load imposed on the track member. This object is realized by providing the track member with a substantial mass of integral metal distributed beneath and underlying substantially the entire area of the portions thereof which are subject to greatest stresses in use, and forming this mass with cavities, recesses, or cored spaces distributed thereover with intervening spaces that leave between them strengthening walls advantageously positioned with reference to strains to be resisted, and having dimensions restricted with in limits which admit of thorough heat

treatment, not only of the entire strengthening mass but of the normal walls of the track member as well. The recesses preferably extend vertically and the intervening walls extend promiscuously from side to side of the member, longitudinally thereof, and on various intersecting lines so that not only do the walls bridge the distance between marginal sustaining flanges or other portions of the track member and resist stresses which tend to crack the member, but they serve as struts or cross braces for one another which greatly increases their trussing effect, and when, as in the preferred construction, they extend vertically to the horizontal plane of supporting surfaces they may, when properly supported, afford direct vertical support to loads imposed upon the track member. The general effect of the construction is cellular and there is constant distribution of stresses imposed transversely upon the walls of the reinforcing mass, although in the preferred embodiment the recesses are defined mainly by arcuate lines which develop fillet effects rather than angles at the intersections of the walls, thereby further safeguarding against the starting of cracks.

In the accompanying drawings, in which the preferred embodiment of the invention is illustrated—

Figure 1 is a top plan view of a railway crossing member in the form of a stub embodying tread portions, intersecting flangeways, and marginal supporting flanges.

Figure 2 is a section on the line 2^x—2^x of Figures 1 and 3.

Figure 3 is a section on the line 3^x—3^x of Figures 2; and

Figure 4 is a section on the line 4^x—4^x of Figures 1 and 4.

1, 1^a represent aligned tread portions for continuing a rail of one track, 2, 2^a represent aligned tread portions for continuing a rail of an intersecting track, and 3 and 4 represent flangeways appurtenant to the respective treads, which flangeways intersect at 5. In addition to these elements, the track member and the crossing member will usually be provided with guard portions 6—6 and 7—7; and the member will usually be provided with supporting and spiking flanges 8, 9.

In forming a crossing section such as here selected for purposes of illustration, and

particularly if formed of cast manganese steel, it has heretofore been customary to core the entire inner portion of the casting on lines which left continual marginal walls corresponding substantially to the portion indicated at 10 in Figure 2, and a continuous top wall such as indicated by the dotted line 11 in said figure, or by the full line 11* in Figure 4, in order to provide beneath the tread portions and flangeways as great a thickness of metal as practicable without defeating the heat treatment of the casting. But this practice gave rise to cracking, which would usually start at the point 5 of intersection of the flangeways and would gradually extend to the ends of the casting; and when, it was sought to remedy this defect by increasing the volume of metal beneath the treads and flangeways, heat treatment was so far impaired as to develop segregation of the constituents of the alloy with consequent hammering down or flowing of the treads, particularly at the points.

According to the present invention, the cavity of the casting is filled by a substantially continuous reinforcing mass 12 cast integrally with and underlying substantially the entire area of the track member and having dimensions which enable it to sustain the track member under all loads that it is called upon to bear, by affording a substantial bridge of the distance between supporting flanges, and, furthermore, by acting as a direct supporting column if the reinforcing mass is given a vertical dimension which brings it to the lower plane of the marginal sustaining flanges 8 and 9. But in order that this reinforcing mass may not defeat the heat treatment of the metal, and in order that stresses which are to be imposed upon it may be distributed to the best advantage and in a manner to insure ample strength in the resultant relatively thin walls, the mass 12 is rendered cellular or recessed throughout by providing a considerable number of isolated corings or cavities 13, 15, 14, 16, and 17, which provide variously extending bridge walls 18, 19, 20, and 21 which intersect and reinforce one another after the manner of trussing; and these corings or cavities extend vertically from the lower plane of the casting toward the treads, guards and flangeways but terminate short thereof distances which leave beneath said treads, guards, and flangeways an ample thickness of metal to insure the integrity thereof under the loads they are intended to bear. The cores are set with particular reference to weaker portions of the track member. For instance, the walls 21 will upon comparison of Figures 1 and 3, be seen to lie transversely beneath flangeways of the member, while the wall 18 bisects the angle of the merging tread portions 1*, 2*, and other walls will be found to approximate

the longitudinal lines of the tread portions, while still others are substantially continuous from one side flange of the track member to the other so as to form sustaining bridges for the whole structure. 70

An important feature of the invention resides in the fact that instead of having supporting flanges on the under side of the casting corresponding in position to the tread and guard rail portions of the member, 75 and with occasional transverse spacing ribs, the under side of the casting comprises a substantially continuous mass underlying substantially its entire area, and in this mass are formed approximately tubular cells 80 or recesses which avoid angles or corners from which cracks can start, and which present the remaining partition walls in such widely diverse positions as to distribute horizontal stresses throughout the mass 85 rather than in limited directions.

I claim:

1. A cast steel track member having upon its under side a substantially continuous integral sustaining mass, and having said 90 mass formed with a plurality of isolated recesses subdividing the mass into variously directed reinforcing walls.
2. A cast steel track member having upon its under side an integral sustaining mass 95 underlying substantially the entire area of the member, and having said mass formed with a plurality of isolated recesses subdividing the mass into variously directed reinforcing walls, some of which underlie longitudinal lines of tread portions of the track member while others extend transversely 100 thereof.
3. A cast steel track member constructed upon its under side with an integral reinforcing mass underlying substantially the entire area of said member formed with a 105 plurality of vertically extending recesses subdividing the mass into variously directed sustaining walls which intersect and truss 110 one another.
4. A cast steel track member having tread and flangeway portions, and having beneath it and underlying substantially its entire area an integral mass of metal formed with vertical recesses spaced apart and leaving between them strengthening walls. 115
5. A cast steel track member having tread and flangeway portions, and having beneath it and underlying substantially its entire area 120 an integral mass of metal formed with vertical recesses spaced apart and leaving between them strengthening walls; some of said walls extending from side to side of said track member.
6. A cast steel track member having tread and flangeway portions, and having beneath it and underlying substantially its entire area 125 an integral mass of metal formed with vertical recesses spaced apart and leaving be- 130

tween them strengthening walls; some of said walls extending from side to side of said track member, and others thereof intersecting and bracing said transversely extending walls.

7. A cast steel track member having tread and flangeway portions; said track member being constructed beneath said portions with a substantially continuous integral reinforcing mass of metal formed with numerous isolated recesses leaving connected walls; said recesses extending vertically toward but terminating short of the tread and flangeway portions, and leaving beneath the latter a horizontally continuous body of metal; the lower plane of said reinforcing mass being coincident with the supporting plane of the track member.

Signed at Illinois, this 24th day of July, 1922.

8. A cast steel track member having tread
